ELECTRIC SWITCH

Richard H. Schmitt, Schenectady, N. Y., assignor
to General Electric Company, a corporation of
New York

Application May 17, 1938, Serial No. 208,385

3 Claims. (Cl. 200—6)

This invention relates to electric switches, and more particularly to switches of the quick make and break type.

It is an object of the invention to provide an improved construction and arrangement in switches of this type having a minimum of parts which may be easily assembled within the switch casing. The construction is reliable in operation and insures a firm and even contact between the 10 switch circuit-closing members.

In the accompanying drawing, Fig. 1 is a sectional view through the switch; Fig. 2 is a plan view of the bottom of the switch with the closure cover removed; Fig. 3 is a perspective view of a portion of the switch-operating mechanism; Fig. 4 is a view substantially along the line 4—4 of Fig. 1 with the switch housing in section; Fig. 5 is a sectional view along the line 5—5 of Fig. 1, and Fig. 6 is a perspective view of a portion of 20 the switch mechanism showing one of the contacts in open and in closed position.

Referring to the drawing, a housing 10, which may be formed of insulating material such as a phenolic condensation product and filler, or 25 the like, is provided for the switch mechanism. The housing is formed at the bottom with a substantially rectangular recess 11 for receiving the contact terminals of the switch mechanism, while a cavity 12 extends from the recess toward the 30 top of the housing for receiving the switch-operating handle. In order to provide for mounting of the switch upon a base the housing is formed with diametrically opposed openings 13.

According to the invention pairs of terminal members 14 and 15 are arranged symmetrically within the recess 11 and are secured to the housing by means of drive pins 16. Each of the terminal members is provided with a terminal screw 17 for connection to the conductors of an electrical circuit. The conductors are led into the body of the switch through the slots 18 which are disposed on opposite ends of the switch housing and which merge with the recess 11. Each of the terminal members 14 is provided with a projecting contact 19, while the terminal members 15 are provided with similar contacts 20.

In each case the contacts of each pair of terminal members cooperate with a corresponding shorting roller or contact 21 mounted in a rocker 22. The rocker 22 is formed of insulating material and is mounted in the housing by means of opposed bearing elements 23 disposed in grooves 24 formed in the housing, the bearing portions being held in the grooves 24 by means of a pin 25 extending through the housing. The pin 25

rests in grooves 26 formed on each side of the housing so that the rocker 22 is pivotally mounted for oscillatory motion to and fro within the housing.

The shorting rollers 21 are resiliently or movably mounted upon the rocker 22 in order to make and break contact with the pairs of contact lugs 19 and 20, respectively. To this end the shorting rollers are disposed in grooves or slots 27 formed in the opposing arms 28 of the rocker. The rollers are maintained in the grooves by the coiled torsion springs 29 which are nested in slots 30 formed in each of the arms 28. The U-shaped end 31 of the coiled torsion springs is disposed within the slot 30 and is retained therein by the pin 32 integral with the rocker, while the opposite prong ends 33 of the torsion springs rest in grooves 34 formed on each of the ends of the shorting rollers and serve to maintain the rollers seated within the slots 27. The torsion springs 29 maintain the shorting rollers securely seated within the slots 27 at all times.

Upon oscillating the rocker to switch-closing position the shorting rollers make contact with the contact lugs 19 and 20. At this time the rocker continues to move to a position beyond that at which the rollers engage the contact lugs so that the rollers are retained against the contact lugs and move a small distance within the grooves 27, as shown by Fig. 6. This relative movement between the rollers and rocker element is permitted by flexure of the torsion springs. The springs now are tensioned further to maintain the rollers firmly against the contact lugs. This construction ensures a firm contact between the rollers and contact lugs under the influence of the torsion springs and thus the contact pressure is not one which depends upon the degree of movement of the rocker element upon operating the switch but depends upon the constant force exerted by the torsion springs.

The rocker is provided with an operating handle 35 which projects through an opening 36 formed in the top wall of the housing adjacent the cavity 12. Upon operation of the handle the switch may take either of two positions to close either the right or left-hand pairs of contacts through the medium of the shorting rollers. In mid-position the switch is "Off". The various positions of the rocker element are determined by a positioning mechanism comprising a plurality of grooves 37 formed integrally on each side of the body of the rocker element which cooperate with projections 38 formed in the side members 40 of a rectangular spring blade. The spring 40

comprises a flexure plate which is compressed between the positioning grooves 37 and the top wall of the housing. Three of the grooves 37 are provided, the center one designating the "Off" 5 position and the two adjacent ones "On" positions. As the switch is moved from one position to the other, the spring 40 is flexed to permit the projections 39 to enter one of the grooves 37.

The recess 11 is closed by a plate 41 of insulating material provided with a centrally disposed upstanding portion 42 which cooperates with a rounded surface 43 on the rocker member to steady it in position. The closure plate is locked to the housing by means of a strap 44 15 having bent-up ends 45 placed over the projections 46 formed on the outside of the housing.

In connecting up the switch the conductors are inserted through the slots or openings 18 and are connected to the terminal screws 17. As the 20 switch is operated to and fro the circuit across the pairs of contact lugs 19 and 20 is closed by means of the shorting rollers 21. In some circumstances, it may be desirable to interconnect two of the terminal members and such a connection is shown at 47. When the switch is turned to circuit-closing position the shorting rollers are brought into contact with the pairs of terminal contacts 19 and 20 and are firmly held against them by the action of the torsion springs 25 30 29 which maintain excellent electrical contact between the contacts and the rollers.

What I claim as new and desire to secure by Letters Patent of the United States is:

1. In combination, a housing, spaced contacts 35 mounted on opposite sides of said housing, a rocker element pivotally mounted in said housing for oscillatory movement between said contacts, said rocker element having a groove and a slot therein, a shorting contact comprising a roller member disposed in said groove, spring means 40 mounted in said slot on said rocker element and having prong ends on each side of said element

engaging said contact to retain it within said groove, said spring means being flexed upon engagement of said shorting contact with said spaced contacts to permit relative movement between the rocker element and shorting contact whereby said spring means maintains said shorting contact in engagement with said spaced contacts. 5

2. In a switch structure, a housing having a recess therein, a rocker element pivotally mounted within said recess and having opposed arms, each of said arms being provided with a groove and a slot therein, a roller contact element mounted in each of said grooves, spring means mounted in each of said slots on said rocker element and each having prong ends disposed on opposite sides of said rocker element for engaging corresponding contact elements and retaining them within said grooves, pairs of contact members mounted in said recess and cooperating with each 10 15 20 25 30 35 40 of said roller contacts, said roller contacts sliding in their respective grooves on engagement with said fixed contacts under oscillatory movement of said rocker element and being held in engagement with said spaced contacts by the prong ends of said spring means.

3. A switch comprising a housing, a rocker element mounted in said housing and having a groove and a slot therein, a roller contact slidably disposed in said groove, spring means mounted in said slot and having prong ends engaging said roller on each side of said rocker element for retaining the contact within said groove, fixed contacts mounted in said housing and disposed on each side of said rocker element for engagement 35 with said roller contact on oscillatory movement of said rocker element, and a flexible leaf spring engaging said rocker element and the wall of said housing to position said rocker element in either contact closing or contact opening position. 40
